UNITED STATES PATENT OFFICE.

HARRY B. JAY, OF CHICAGO, ILLINOIS.

DRUM-SNARE.

1,265,917.

Specification of Letters Patent. Patented May 14, 1918.

Application filed June 2, 1917. Serial No. 172,429.

To all whom it may concern:

Be it known that I, HARRY B. JAY, a citizen of the United States of America, and a resident of Chicago, county of Cook, and 5 State of Illinois, have invented certain new and useful Improvements in Drum-Snares, of which the following is a specification.

The main objects of this invention are to provide an improved form of drum snare which is independent of atmospheric temperature and humidity conditions and of the surface conformation of the drumhead; to provide an improved snare for drums in which the snares may be readily shifted into 15 and out of contact with the drumhead; and to provide improved means for adjusting the tension of the snares against the drumhead.

An illustrative embodiment of this invention is shown in the accompanying drawings, in which—

Figure 1 is a vertical section of the lower portion of a drum, showing the improved snare attached thereto.

Fig. 2 is a plan view of the side of the improved snare which is adjacent the drumhead when in use.

Fig. 3 is a section on the line A—A of Fig. 2.

In the use of snare drums, it is highly desirable to have a snare which can be readily brought into use and shifted to a position out of contact with the drumhead, without the manipulation of cumbersome clamps and analogous means. It is also desirable to have a construction in which the contact of the snares with the drumhead can be varied readily to render them more or less sensitive to vibration and in which a quick 35 adjustment may be made to suit changes in the drumhead occasioned by moisture or weather conditions.

In the construction shown in the drawings, the improved drum snare comprises an elongated base member 1 provided at its opposite ends with suitable clips 2 and 3 with which it is adapted to be rigidly mounted on the tightening hoop 4 of a drum adjacent the head 5 thereof. The snares 45 comprise a plurality of resilient fingers in the form of slender spring wires 6, each of which is rigidly mounted at one end on a transverse clamping bridge or supporting

member 7. The bridge member 7 is provided with a plurality of holes each of which is 55 adapted to receive one end of one of the resilient fingers 6, and the fingers 6 are clamped in their respective positions by set screws 8 threaded in the bridge member 7, one of which is provided for each finger. The 60 member 7 is carried by legs at its ends pivotally mounted by suitable screws 9 and 10 on the base member 1 adjacent one end thereof and extends transversely thereto.

Means are provided for rocking the bridge 65 member 7 so as to carry the free ends of the resilient fingers 6 away from the drumhead and comprise a compression spring 11 mounted in a recess 12 in the base member 1 in position to bear between the base member 70 and an arm 13 which is formed integrally with the bridge member 7. When the bridge member is normally rocked under action of the spring 11, the free ends of the fingers 6 rest upon a deadening pad 14 of suitable 75 material such as felt, or the like.

The bridge member 7 is adapted to be rocked against the action of the spring 11 so as to carry the free ends of the fingers into contact with the drumhead 5, by an adjustable camming device, preferably in the form of a threaded thumb screw 15 which is threaded through a manipulative member or rod 16 transversely to the axis thereof, the manipulative member being journaled by 85 suitable supporting clips 17 on the under side of the base member 1. The outer end 18 of the thumb screw 15 is adapted to extend through an aperture 19 in the base member 1, so as to contact with and shift 90 an arm 20 formed integrally with the supporting bridge 7 and extending outwardly therefrom on the opposite side from the arm 13. Adjustment of the pressure of the snare-fingers upon the head of the drum is accomplished by turning the screw 15 on its own 95 axis.

The manipulative member 16 is adapted to be readily rotated on its axis so as to shift the arm 20, by means of a knurled 100 thumb nut 21 rigidly mounted on the outer end thereof.

In the operation of the device, the base member is mounted on the under side of a drum on the tightening hoop 4 by means 105 of the clips 2 and 3. When it is desired to

bring the snare into use, the knurled thumb nut 21 is grasped by the user and rotated, thus causing the end 18 of the thumb screw 15 to cam the arm 20 upwardly, thus rocking the supporting member 7 and thereby shifting the free ends of the resilient fingers 6 into contact with the drumhead 5. The pressure of the fingers 6 bearing on the underside of head 5 tends to support and tighten the drum head regardless of whether the head be flat or warped or be loose because of dampness in the atmosphere; and being of metal, the fingers themselves are not affected by atmospheric conditions as are the usual gut snares. The slot 19 is so arranged that the thumb screw 15 may be rocked slightly past center, as shown in dotted outline in Fig. 3, thereby utilizing the pressure of the spring 11 for locking the snares in their operative position.

When it is desired to shift the snares out of contact with the drumhead, the thumb nut 21 is rotated in the opposite direction, and the compression spring 11 thereupon shifts the arm 13 upwardly and rocks the supporting member 7 so as to carry the free ends of the resilient fingers 6 out of contact with the drumhead 5 and into contact with the pad 14.

Although but one specific embodiment of this invention has been herein shown and described, it will be understood that numerous details of the construction shown may be altered or omitted without departing from the spirit of this invention as defined by the following claims.

I claim:

1. A snare for drums, comprising a supporting member, means for pivotally mounting said member on a drum adjacent the head thereof, a plurality of resilient fingers rigidly mounted on said supporting member, and means for rocking said supporting member so as to shift said fingers into and out of contact with such drumhead.

2. A snare for drums, comprising a base member, means for rigidly attaching said member to a drum adjacent the head thereof, a plurality of resilient fingers shiftably mounted on said base member, yielding means for normally urging said fingers out of contact with such drumhead, and means for shifting said fingers into contact with such drumhead.

3. A snare for drums, comprising a base member, means for rigidly attaching said member to a drum adjacent the head thereof, a clamping member movably mounted on said base member, a plurality of resilient fingers rigidly mounted at one end on said clamping member, yielding means for normally rocking said clamping member so as to carry the free ends of said members away from such drumhead, and cam means for rocking said clamping member so as to

carry said free ends into contact with such drumhead.

4. A snare for drums, comprising a base member, means for rigidly attaching said member to a drum adjacent the head thereof, a plurality of resilient fingers shiftably mounted on said base member, yielding means for normally urging said fingers out of contact with such drumhead, a manipulative member journaled on said base member, and a cam on said manipulative member for shifting said fingers into contact with such drumhead.

5. A snare for drums, comprising a base member, means for rigidly attaching said member to a drum adjacent the head thereof, a plurality of resilient fingers shiftably mounted on said base member, yielding means for normally urging said fingers out of contact with such drumhead, a manipulative member journaled on said base member, and an adjustable cam on said manipulative member for shifting said fingers into contact with such drumhead.

6. A snare for drums, comprising a base member, means for rigidly attaching said member to a drum adjacent the head thereof, a plurality of resilient fingers shiftably mounted on said base member, means for shifting said fingers into and out of contact with such drumhead, and a deadening pad on said base member adapted to have said fingers rest thereon when in one position.

7. A snare for drums, comprising a base member, means for rigidly attaching said member to a drum adjacent the head thereof, a clamping bridge pivotally mounted on said base member, a plurality of spring wires rigidly mounted at one end on said clamping bridge, a deadening pad on said base member adapted to have the free ends of said wires rest thereon, yielding means for normally rocking said clamping bridge so as to carry the free ends of said wires into contact with said pad, a manipulative member journaled on said base member, and an adjustable cam on said manipulative member for rocking said bridge against the action of said yielding means so as to shift the free ends of said wires into contact with such drumhead.

8. A snare for drums, comprising an elongated base member, means for rigidly attaching said member to a drum adjacent the head thereof, a clamping bridge pivotally mounted on said base member adjacent one end thereof and transversely thereto, a plurality of spring wires rigidly mounted at one end on said clamping bridge, a deadening pad on said base member adapted to have the free ends of said wires rest thereon, said clamping bridge having a part extending at each side thereof, a compression spring bearing between one of said

parts and said base member for normally
rocking said bridge so as to carry the free
ends of said wires into contact with said
pad, a manipulative member journaled on
5 said base member, and an adjustable cam
on said manipulative member adapted to
coact with the other of said bridge parts

for rocking said bridge so as to shift the
free ends of said wires into contact with
such drumhead.

Signed at Chicago this 31st day of May
1917.
